US0D1034094S

(12) **United States Design Patent** (10) **Patent No.:** **US D1,034,094 S**
(45) **Date of Patent:** **** Jul. 9, 2024**

(54) **INSULATING DEVICE**

(71) Applicant: **YETI Coolers, LLC**, Austin, TX (US)

(72) Inventors: **Roy Joseph Seiders**, Austin, TX (US);
Derek G. Sullivan, Austin, TX (US);
Erik Steven Larson, Austin, TX (US);
Alex Baires, Austin, TX (US)

(73) Assignee: **YETI Coolers, LLC**, Austin, TX (US)

(**) Term: **15 Years**

(21) Appl. No.: **29/825,281**

(22) Filed: **Jan. 31, 2022**

Related U.S. Application Data

(63) Continuation of application No. 29/784,004, filed on May 17, 2021, now Pat. No. Des. 942,222, which is a continuation of application No. 29/753,836, filed on Oct. 2, 2020, now Pat. No. Des. 919,376, which is a continuation of application No. 29/703,088, filed on Aug. 23, 2019, now Pat. No. Des. 897,780, which is a continuation of application No. 29/624,126, filed on Oct. 30, 2017, now Pat. No. Des. 862,177, which is a continuation of application No. 29/553,995, filed on Feb. 5, 2016, now Pat. No. Des. 801,123.
